SPEED REGULATOR

George E. Howard, Butler, Pa.

Application December 17, 1937, Serial No. 180,295

11 Claims. (Cl. 123—102)

regulators and the slight diffe

My invention relates to speed regulators and more particularly to those of the type employed for governing the speed of motor vehicles or the speed of their motors.

6 Governor of forms heretofore employed are
7 objectionable in that they usually have direct con-
8 nection with a throttle valve that controls ad-
9 mission of the explosive mixture to the motor,
10 and they usually so operate that the range of
11 their control is over a spread of five to ten miles
12 per hour variation. For example, if a centrifugal
13 governor is set to prevent the motor running at a
14 speed which will move the vehicle faster than
15 50 miles per hour, upon deceleration through
contractive movement of the governor, the rate
of vehicle travel may decrease to the extent of
perhaps five or ten miles per hour.

20   Motor vehicles are manually controlled, usually through a foot-actuated throttle. It is desirable to have quick control of this throttle from closed to open position in order to give quick acceleration especially at low speeds. As the car attains a higher speed and especially when it reaches the maximum allowable speed, it is desirable to have an automatic speed regulator or governor to insure keeping within the legal speed. At the maximum speed, the car will not respond so quickly to an increase of power as the momentum of the car and its parts is such that acceleration is somewhat slower, and this is desirable because sudden acceleration and deceleration take up the lost motion between the driver, which is the engine, and the driven parts, which are the wheels, and cause a jerky motion which is uncomfortable to the driver and hard on the mechanism generally. This is a reason why in governors, which are directly connected to the throttle, that a considerable range of speed is necessary to effect the throttle opening from completely closed to completely open position. Otherwise, if such a governor is arranged so that it makes this complete movement of throttle for a slight difference of speed, the jerky application and cutting off of power would cause the objection above named.

Changes in load on a car, as from upgrade to downgrade, wind resistance, etc. are not very sudden, as ordinarily the variable load caused by gravity corresponds to the rise or fall of the road-way, which ordinarily is not sharp. A car will travel a considerable distance for a considerable time at maximum speed with very little change in the load variation. This will be true whether running on a level or going up or down grades. When the ordinary governor, therefore, is used,

the slight difference in throttle position caused by minor speed changes, usually is sufficient to accelerate or decelerate engine speed. The position of the throttle being roughly proportional to the load on the engine, this position may vary widely, depending upon whether the engine is called upon to take care of a heavy load or pull, or a light one. 5

With ordinary governors, particularly those of the centrifugal type and having, as explained above, a considerable range of speed between full load and no load, there is very little variation at any one load. The objection, therefore, is that at full load the motor car will have to run at the lower rate and at a lighter load it can run at the maximum rate. Inasmuch as the allowable speed limit is not dependent upon the grade, it compels the driver to travel much of the time well below the maximum allowable speed limit and thus lose time and distance.

One object of my invention is to provide means whereby notwithstanding these slight variations of "load" changes and speed, a given engine speed will be obtained by the governor at substantially all loads.

Another object of my invention is to provide means whereby a sudden motion imparted to the governor, which may be caused by jolting and bumping and not by speed, will not make a correspondingly rapid change in the position of the throttle and a sudden change of power, thus providing a more stable and smoother operation. 29 30

These and various other objects are obtained by means of apparatus illustrated in the accompanying drawings, wherein Figure 1 is a side view of an automobile motor equipped with my invention; Fig. 2 is an end view partially in section; Fig. 3 is an enlarged view taken on the line III—III of Fig. 2; Fig. 4 is a view taken on the line IV—IV of Fig. 3; Fig. 5 is a view similar to Fig. 4 but showing a modification of the apparatus, and Fig. 6 is a view showing still another modified form of the controlling apparatus.

Referring first to Figs. 1 to 4, the vehicle motor is indicated by the numeral 8 and is provided with the usual intake manifold 9, fuel supply pipe 10, carburetor 11 and throttle valve 12 which is actuated through the usual pull rod 13 that is connected to a foot pedal (not shown). The governor as a whole is indicated by the numeral 14 and operates a pull rod or link 15 and a crank 16 to turn a control valve 17 which may be in the form of an ordinary throttle valve. The link 15 has ball and socket connection at one end with the crank 16 and at its other end has ball and

socket connection with a toothed segment 18 that is pivotally mounted on a stud 19 which is carried by the governor casing 20. A spring 21 anchored at one end to the casing 20 and at its other end to the segment 18 serves to yieldably hold the control valve 17 in open position, as shown more clearly in Fig. 4. An adjustable stud 22 determines the distance which the segment 18 may be turned against the tension of the spring 21 toward valve-closing position.

The governor is driven by a shaft 24 which is here shown as disposed in the motor casing and which may be the usual cam shaft of the motor if control of engine speed is primarily desired. In cases where a more direct control of vehicle speed is desired, the governor may have driving connection with the speedometer shaft or the transmission shaft. The shaft 24, through suitable gears 25, drives a shaft 26 which carries a pinion 27 that meshes with a gear wheel 28 carried by a shaft 29. The shaft 29 extends upwardly into the governor casing 20 and is supported in suitable bearing bushings 30, 31 and 32, the upper end of the bushing 32 abutting against a screw stud 33 threaded into the upper side of the casing.

A governor plate 34 has a lower hub portion secured to the shaft 29 by a stud or key 35. A camming member 36 is loosely mounted on the shaft 29 and has limited rotary or oscillatory movement relative to the plate 34 and the shaft 29, and is provided with a pair of upstanding camming lugs or shoulders 37 which are diametrically opposite to one another. A pair of governor weights 38 are pivotally connected at 39 to the plate 34 and each has a downwardly-extending guide pin or stud extending into an arcuate slot 40. Each of the weight members 38 is held in its contracted position, as shown in Figs. 3 and 4, by a spring 41. The inner end of each weight member is connected through a link 42 with the oscillatory camming member 36. It will be seen that when the shaft 29, and consequently the governor plate 34, is driven at a sufficiently high speed, the said members 38 will swing outwardly about their pivots 39 thus imparting some rotative movement to the camming member 36 upon the governor plate 34 and relative to the shaft 29. This form of governor is of somewhat conventional type, and governors of other forms could be substituted therefor.

A plate or disc 44 is slidably keyed to the shaft 29, as indicated at 45, so that it will rotate with the shaft but can have movement longitudinally thereof. The plate has downwardly-extending shoulders 46 which have recesses formed therein for cooperation with the camming shoulders 37 of the governor. The plate 44 is yieldably urged in its downward direction by a spring 47 that is interposed between the upper side of the plate and the bearing bushing 32.

The plate has upstanding sleeve-like portions 48 for supporting shoes or clutch elements 49 that have studs 50 which extend through slots in the walls of the sleeves 48 to prevent displacement of the shoes but permitting vertical movements thereof. A spring 51 is interposed between the under side of each shoe 49 and a screw stud 52 which is adjustable to vary the spring pressure with which the shoe 49 is urged upwardly.

A clutch plate 53 has a hub portion which loosely surrounds the bearing bushing 32 and is vertically supported thereon by screw studs 54 which extend through a flange of the cover plate

55 of the governor casing and into an annular groove in the said hub portion of the clutch plate. The clutch plate is provided with gear teeth on its periphery which mesh with the teeth of the segmental disc 18, so that when rotative movements are imparted to the clutch plate 53, the plate 18 will be rocked to operate the control valve 17.

It will be seen that when the engine or vehicle, as the case may be, exceeds a predetermined speed, the governor weights 38 will move outwardly at their inner ends, thus imparting rotary movement to the camming member 36 and thereby forcing the plate 44 upwardly. Upon upward movement of the plate, the clutch shoes 49 will engage the under side of the clutch plate 53. The shoes 49 will at first slip on the plate 53, so that the disc 53 will not immediately be rotated at the same rate as the shaft 29. This slippage results in delayed or slower movement of the segmental plate 18 against the tension of its spring 21 so that the control valve 17 is not abruptly or too quickly moved in a closing direction.

The slippage will be less when there is a more abrupt increase in speed of the shaft 29, and this is desirable because it is desirable that the supply of fuel and the power closely follow any change in speed which it is the object of the governor to control. As the speed is always caused by a change in load at a fixed throttle position, this quick response of fuel application and power to the load is desirable. Conversely, when there is a slight change in speed, the slippage will be greater, but here the movement of the throttle valve has to be less in order to effect a balance between the supply of fuel and load, and in consequence this mechanism permits of either a sudden change of speed or a slight and slow increase of speed with the same smooth action or operation. Adjustment of the tension of the spring 21 will be made to effect desired slippage of the shoes during slow retraction or at slight retractions of the governor, thus effecting an easing from closed throttle to open throttle position. When the control valve is wide open—below the governing point—and the governor expands, the clutch will first slip against the force of the spring 21, thus slightly delaying valve closing.

When the clutch has caused the valve 17 to be moved to its extreme closed position, the shoes 49 will simply slip on the clutch plate 53. At a stage where the governor weights 38 are not fully expanded, the shoes may not have sufficient pressure against the clutch plate 53 to fully overcome the tension of the spring 21, with the result that the valve 17 will not be moved to its fully retarding position, thus making for smoother movement of the motor. The gear ratio of the segment 18 and plate 53 can be changed in order to give desired ranges of movement of the valve 17 upon given movement of the plate 53, and this will result in change of time ratio.

Similarly when the speed of the vehicle or of the engine is reduced below a predetermined point, the clutch elements 49 and 53 will be caused to separate and the spring 21 will cause return of the valve 17 to its open position, the return movement being retarded somewhat by the friction of the shoes 49 before they have been entirely separated from the clutch plate 53.

The tension of the springs 51 and hence that point in the upward movement of the disc 44 where the shoes become effective to drive the disc 53 is adjusted by the screws 52.

From the foregoing, it will be seen that there

is a delayed or retarded movement as between the governor and the control valve, with the result that there is more gradual movement of the valve 17 relative to the governor and that slight fluctuations in governor speed will not cause corresponding movements of the control valve, so that there is absence of unnecessary accelerating and decelerating impulses in the engine and mechanism of the car.

In Fig. 5 I show another form of governor structure wherein a generator 57 of somewhat usual form, having a shaft 58, is driven by the engine through gears 59, in a manner similar to that shown in Figs. 2 and 3. The shaft 58 carries a disc 60 and also has loosely mounted thereon a disc 61. The disc 61 carries solenoids 62 which comprise an opening coil and a movable core 63, the core 63 being provided with a downwardly-projecting stem which carries a shoe 64 and being yieldably held in its uppermost position by a spring 65. The disc 61 has teeth on its periphery that mesh with the teeth of the segmental disc 18.

The generator is of such form as will produce current which will vary with variations in speed of the shaft 58, and such current flows through the operating coils of the solenoids 62 by way of conductors 66.

It will be seen that as the speed of the shaft 58 increases to a point approximating that at which the governor is to be actuated, the value of the generated current will be sufficient to cause the cores 63 to be moved downwardly against the springs 65 and the shoes 64 to be brought into engagement with the disc 60, so that rotative movement is imparted to the disc 61 to rock the toothed segment 18 and move the control valve 17. The degree of slippage will depend upon the magnetic force, and such magnetic force will, of course, be increased or decreased with the changes in speed of the shaft 58.

Referring now to Fig. 6, I show a generator 68 which is driven from a moving part of the engine or of the transmission mechanism, through a shaft 69 and belt 70. The output of the generator will, of course, depend upon the speed of the driving members. Current from the generator is supplied through conductors 71 and 72 to a motor 73, which through driving shaft 74 and a pinion 75 effects rotative movement of a gear wheel 76 that through a link 77 is connected to the crank 78 of a control valve 79. A spring 80 anchored at its ends to the crank 78 and to a fixed point on the fuel intake line 81, respectively, yieldably holds the valve 79 in its open position. Adjustable stop screws 82 and 83 limit the range of movement of the crank 78 and hence of the valve 79.

At slow speeds the generator does not have sufficient output to drive the motor 73. As the speeds increase, the motor 73 will be set into motion to drive the gear wheel 76 and to move the valve 79 toward retarding position, such movement being resisted by the spring 80. Therefore, the extent to which the valve 79 is moved will depend upon the rate at which the generator is driven. When the torque of the motor and the tension of the spring are balanced, movement of the valve will cease. Therefore in this form of apparatus there is what may be termed a magnetic slip as compared to the mechanical or frictional slip of the other structures.

The essence of this invention is that the governor will operate through a close range of speed, say from 49 to 50 miles per hour, just as the

ordinary governor will, but it will have the advantage that it will carry this same range or other desired range of speed for all loads from zero to full, whereas, the ordinary governor will require a difference between 50 to 45 miles to effect the same thing. 5

Stated in other words, an example of the primary functional difference between my forms of governor as above described and the governors of the prior art, arises out of the fact that with an ordinary governor which at a vehicle speed of say 50 miles per hour will have closed the throttle, full throttle opening cannot be had until the vehicle has decelerated to 45 miles per hour or less. This is an objectionable feature—particularly if at said maximum speed and closed condition of the throttle the vehicle passes from say a level stretch of road or downgrade to uphill, because full throttle opening is then instantly desired in order to maintain the maximum speed. This full throttle opening cannot be had until said deceleration is effected, with consequent unnecessary slowing down of the car and perhaps inability thereafter to attain the desired speed on the hill. On the other hand and under the same maximum speed condition, with the throttle closed, my governor apparatus is such that the throttle valve will be permitted to open fully upon deceleration to probably not lower than 49 miles per hour, instead of such opening being delayed until deceleration to 45 miles per hour, and my throttle will not begin to close until a speed of approximately 50 miles per hour has been again attained. In the prior governors, the throttle would begin to close at about 45 miles per hour. 25

I claim as my invention:

1. The combination with an engine and a source of motive fluid therefor, of a valve for controlling flow of said fluid to the engine, a speed governor driven from the engine, and a device actuated by the governor, through a slip drive and against gradually increasing resistance for so moving the valve during a predetermined minimum speed and range of speed variation, as to maintain the engine at approximately the same speed under one engine load as under another and different engine load at the same minimum speed and range of speed variation. 45

2. The combination with an engine and a source of motive fluid therefor, of a valve movable to control flow of said fluid to the engine, a speed governor driven from the engine, a frictional driving connection between the governor and the valve, and means for variably opposing slippage in said connection. 50

3. The combination with an engine and a source of motive fluid therefor, of a valve movable to control flow of said fluid to the engine, a speed governor driven from the engine, a frictional driving connection between the governor and the valve, and means for opposing slippage in said connection, to an adjustable degree. 60

4. The combination with an engine and a source of motive fluid therefor, of a valve for controlling flow of said fluid to the engine, a speed governor driven from the engine, and a yieldable frictional driving connection between the governor and the valve, the degree of yieldability being adjustable independently of the 70 governor. 65

5. The combination with an engine and a source of motive fluid therefor, of a valve for controlling flow of said fluid, a member for moving the valve, a speed governor driven from the 75

engine, and a frictional driving connection between the governor and said member, calibrated to provide slippage in said connection.

6. The combination with an engine and a source of motive fluid therefor, of a valve for controlling flow of said fluid to the engine, a member operable to actuate the valve, a speed governor driven from the engine, a member driven by the governor and effective to move the first-named member, when the governor reaches a predetermined speed, and means for retarding movement of the valve-actuating member relative to the second-named member.

7. The combination with an engine and a source of motive fluid therefor, of a throttle valve for controlling flow of said fluid to the engine, a member operable to actuate the valve, a speed governor driven from the engine, a member driven by the governor and effective to move the first-named member, when the governor reaches a predetermined speed, and means for exerting a variable opposing force to said movement at various positions of throttle valve movement.

8. The combination with an engine and a source of motive fluid therefor, of a valve for controlling flow of said fluid to the engine, a member operable to actuate the valve, a speed governor driven from the engine, a member driven by the governor and effective to move the first-named member, when the governor reaches a predetermined speed, means offering variable opposing force to valve movement, and means

for adjusting the degree of said variable opposing force.

9. The combination with an engine and a source of motive fluid therefor, of a valve for controlling flow of said fluid to the engine, an oscillatable member for actuating the valve, means for yieldably holding said member in one position, a speed governor driven from the engine, a member driven by the speed governor, and a frictional driving connection between the last-named member and the oscillatory member, the degree of friction being sufficient to effect movement of the oscillatory member in opposition to said yieldable means, but permitting relative slippage of said two members.

10. The combination with an engine and a source of motive fluid therefor, of a valve for controlling flow of said fluid to the engine, a member operable to actuate the valve, means driven by the engine for generating an electro-motive force, and means operated by said force for moving the said valve-actuating member.

11. The combination with an engine and a source of motive fluid therefor, of a valve movable to control flow of said fluid to the engine, a speed governor driven from the engine, an automatically variable driving connection between the governor and the valve, and means exerting a variable opposing force to movement of the valve, the variations in rate of transmission through the driving connection being effected by predetermined changes in governor movement.

GEORGE E. HOWARD.
